E. S. GARDNER.
FILAMENT MOUNTING.
APPLICATION FILED DEO. 27, 1910.

1,089,759.

Patented Mar. 10, 1914.

UNITED STATES PATENT OFFICE.

EDGAR S. GARDNER, OF ACQUACKANONCK, NEW JERSEY, ASSIGNOR TO GENERAL ELECTRIC COMPANY, A CORPORATION OF NEW YORK.

FILAMENT-MOUNTING.

1,089,759.

Specification of Letters Patent. Patented Mar. 10, 1914.

Application filed December 27, 1910. Serial No. 588,357.

To all whom it may concern:

Be it known that I, EDGAR S. GARDNER, a citizen of the United States, residing at Acquackanonck, county of Passaic, State of New Jersey, have invented certain new and useful Improvements in Filament-Mountings, of which the following is a specification.

My invention relates to filament mounting, and its object is an improved mounting which possesses various desirable characteristics and is suitable for filaments and other conductors.

Among the advantages which may be secured in a mounting constructed according to my invention are the following: first, the mounting of a great length of conductor in a small space; second, reduction of the risk of short-circuiting; third, operation of the apparatus with the above advantages in any position, adaptation for service in which it is subject to vibration and shocks, and longer life.

Other advantages will hereinafter appear.

My invention is especially useful in incandescent filament electric lamps; and I have hereinafter particularly described a construction embodying it that is well suited for this purpose, referring to the conductor with which it is used as a filament and to the apparatus in which it is employed as a lamp. The invention can, however, be otherwise carried out and applied. It may be used for the mounting of filaments of tantalum, tungsten, or any refractory metals or materials.

The accompanying drawing gives a perspective view of one embodiment of the invention, the same being shown as broken away from the globe and removed therefrom for the sake of clearness of illustration. To avoid confusion, portions of filament in front of a median plane through the mount are shown in full lines and portions to the rear of such a plane in dotted lines.

The filament system or mount here shown comprises a plurality of filament-carrying elements or arms of iron, nickel, copper, molybdenum, or other suitable material (due regard for the material of the filament being of course had in the selection of the material of the arms) having suitable filament-engaging portions and projecting from supporting means consisting of a member or standard S and a suitable member or base D to which said member or standard S is

attached. These members S and D may be regarded as constituting a single supporting member M. The member or base D may conveniently be a suitable fixed part of the general lamp structure,—and, in particular, 60 the ordinary glass stem through which the current-supply conductors l, l are introduced into the lamp. The engaging portions of the filament-supporting arms or carriers do not all project the same distance 65 from the member M; and in the drawing the carriers (a and b respectively) which lie toward each end of the filament system are shown as varying among themselves as regards projection of their engaging portions 70 from the member M. Furthermore, these carriers a and b are shown as forming suitably separated groups or sets A and B, respectively; and successive carriers of both groups which extend radially from the member S are shown as differing in character as regards projection of their engaging portions 75 from the member S, and, specifically, as relatively "long" and "short" alternately. When the system is viewed end-on, the filament-engaging portions of these carriers appear as staggered. With the exception of the carriers a₁ and a₂₅ of Group A formed by portions of the leading-in wires l, l extending within the lamp globe, all the 80 carrying elements of each group are shown as projecting from a relatively narrow zone 85 in the length of the member S; and, in fact, as being fused into glass enlargements or disks on the said member S. The short carriers of each group may advantageously 90 make somewhat smaller angles with the member S than do the long carriers, as shown in the drawing.

On the supporting system are arranged 95 the filament lengths or sections f, shown as slightly "crimped." From its connection with the end 1 of the left-hand current lead which forms the carrier a₁, the filament extends upward to the engaging portion 2 100 of a long carrier or holder b₂, thence downward to a long carrier a₃, thence upward to a short carrier b₄, thence downward to a short carrier a₅, thence upward to long carrier b₆, thence downward to a long carrier a₇, thence upward to a short carrier b₈, etc., 105 passing finally downward from the engaging portion 24 of the short carrier b₂, to the engaging portion 25 of the carrier a₂₅ formed by the right-hand current lead and 110

being suitably connected thereto. To avoid confusion of reference characters, only the carriers above mentioned are marked with their appropriate subscript letters on the drawing; but the engaging portions of all the carriers are marked with their proper reference numerals 1, 2, 3—23, 24, 25, in order that the filament may be easily followed through its entire length. It will be understood that the engaging portions of the various carriers may have the form of open hooks while the filament is being applied to the system and that such hooks may afterward be closed to form eyes; also that the carriers may be bent and manipulated after the filament has been placed on them, and that their original angles with the member M may be altered so as to bring the filament sections to a proper degree of tautness, etc. When a number of sections are comprised in one continuous piece of filament (as in the specific mount illustrated), the arrangement of the long carriers of a group so as to make a greater angle with the member S than do the short carriers facilitates the application of the filament to the system by making it unnecessary to carry the filament up (or down) between two long carriers in order to place it in the hook of a short carrier.

It will be observed that in the mount hereinbefore specifically described and illustrated, neighboring ones of the set of filament sections have both a component of relative inclination in the direction of the general sweep of the successive filament sections and a component of relative inclination in a lateral direction with reference to the general sweep of the sections,—this lateral direction being in each case approximately coincident with a radial direction with reference to the member S. If the filament sections were arranged in a cylindrical or conical surface of some sort, only the first-named component of relative inclination in the direction of the general sweep of the successive sections would exist. It follows that for the same number of filament sections and approximately the same general dimensions, neighboring sections will diverge more and be better separated in my present type of mount than in one of the type just mentioned. Hence the risk of short circuit through the coming together of neighboring filament sections from any cause will be less in my present type of mount and the average life of the lamp will be correspondingly longer. This means that for the same general dimensions my present type of mount allows a greater number of filament sections to be used without unsafe proximity between neighboring sections and that in consequence a greater total length of filament can safely be mounted in the same space.

In the type of filament system shown in the drawing, a staggered arrangement of the filament-engaging portions of the carrying elements at one end, at least, of the system will always be found very advantageous; and in systems in which a number of sections are comprised in a single continuous piece of filament (as also shown in Fig. 1), such a staggered arrangement will be found desirable at both ends of the system.

What I claim as new and desire to secure by Letters Patent of the United States, is,—

1. In an incandescent lamp, the combination of a central supporting stem, a plurality of groups of alternately long and short filament carriers mounted on said stem, a continuous filament extending back and forth between the carriers of said groups in a plurality of sections, filament sections adjacent to a carrier of one group, extending to carriers of the other group which differ from one another in length.

2. In a filament system the combination of a central supporting stem, two suitably spaced groups of filament carriers mounted thereon, the engaging portions of the carriers of each group being alternately relatively long and relatively short distances from said supporting stem, a continuous filament mounted on said carriers in a plurality of successive sections in such manner that when the first section under consideration is parallel with said supporting stem, the second section forms an angle therewith, the third section is parallel with said supporting stem and the fourth section forms an angle reverse to the angle of said second section with respect to said supporting stem.

3. In a filament mount, the combination of a suitable supporting member and a plurality of carriers at each end of the mount alternately projecting relatively long and relatively short distances radially from said member, and a filament extending back and forth in a plurality of lengths from one end of the mount to the other on said carriers, the filament after passing from a long carrier at one end of the mount to a long carrier at the other extending in successive lengths back again to a short carrier at the end of the mount first referred to, then from this short carrier to a short carrier at the other end, then back yet again to a long carrier at the end of the mount first referred to, in further lengths traversing long and short carriers in like order of succession.

4. In a filament mount, the combination of two separated groups of carriers radiating from a supporting member, the carriers of each group being relatively long and relatively short alternately, and a filament extending back and forth between the carriers of the two groups in a plurality of lengths, lengths extending between long carriers in the respective groups and lengths

extending between the short carriers adjacent to such long carriers having their opposite ends directly connected by lengths which extend from a long carrier of one group to a short carrier of the other and thus have a component of divergence from the lengths which they connect radially with reference to said member, and the short carriers of each group making smaller angles

with the supporting member than do the 10 long carriers so as to facilitate the stringing of the filament.

In witness whereof, I have hereunto set my hand this 23d day of December, 1910.

EDGAR S. GARDNER.
